VALVE ACTUATING MECHANISM

Leavern I. Plank, Santa Barbara, Calif., assignor
to Shell Development Company, San Francisco,
Calif., a corporation of Delaware

Application April 26, 1944, Serial No. 532,914

4 Claims. (Cl. 74—2)

1

The present invention relates to tanks and tank trucks and more particularly to safety means for controlling the discharge valves from such equipment.

In certain types of tank units, particularly tank trucks for delivery and dispensing of gasoline to service stations and the like, the truck tank is commonly provided with a plurality of separate compartments for different grades of gasoline as well as other inflammable materials, such as fuel oil, kerosene, solvents, etc. Each compartment is provided with a separate discharge control valve and delivery conduit, each valve being individually and manually controlled. The control valves are also usually each provided with a safety mechanism such as a fusible metal section in the valve handle, in order to provide automatic closing of the valve in the event of fire in the vicinity of an open valve. A manually operable remote control is generally also included in order that all of the valves which may be opened at any given time may be simultaneously closed from the side or end of the truck opposite from that on which the discharge valves are positioned.

It is an object of the present invention to provide improved means associated with the individual valves of a plurality of tanks or compartments for closing the valves in an emergency. Another object is to provide improved fusible link means associated with said valves adapted to close automatically and simultaneously all the valves in the event of fire in the vicinity of one of the valves. A further object is to provide improved control means of this type which may be easily and rapidly reset after having been activated during an emergency. A still further object is to provide manual and automatic control means which are readily and inexpensively adaptable for use on existing tank systems. Other objects, together with some of the advantages to be derived in utilizing the present invention, will become apparent from the following detailed description thereof, taken together with the accompanying drawings wherein

Figure I is a perspective view of a valve control assembly according to the invention.

Figure II is a plan view of the valve control mechanism as applied to a single valve.

Figure III is a side elevation taken along III—III of Figure II.

In the drawings, a conventional self closing, spring loaded valve is indicated at 1, the valve stem 2 being rigidly attached to a valve handle 55

2

5 which is pivotably joined at 4. In Figure III, the valve handle 5 is shown in the position it takes when valve 1 is open, the valve normally tending to return to a closed position, moving valve handle 5 to the position shown in dotted outline in so doing. Delivery conduits as at 17 are provided in flow communication at each valve.

Rigidly attached to each valve housing is a bracket as at 6, alternate brackets having support arms as at 25 extending forward to support operating rod 9 in slidable relationship therewith as at 8. Each bracket 6 is provided with a projection 7 terminating above valve handle 5 (when the valve is in the open position) and extending outwardly from the valve housing a distance slightly less than the length of valve stem 2.

An operating arm 15 depends downwardly from and is rigidly attached to rod 9 opposite each valve, a contact plate as at 16 being rigidly mounted on each operating arm. Operating rod 9 is normally urged to the right in Fig. I by spring 11 attached thereto at one end, the other end of spring 11 being attached to a stationary point, as for example a bracket 6, by means of metal guy 10. A second spring 12 is attached to the opposite end of operating rod 9 at 25 and normally urges operating rod to the left in Figure I in opposition to spring 11. Spring 12 is anchored at its other end to a stationary point 30 on or near the valve furthest removed from the point of attachment of spring 12 to operating rod 9, a plurality of metal guys 13 with interposed fusible metal links 14 and an adjustment turnbuckle 24 serving to connect spring 12 to 35 the stationary support. Turnbuckle 24 is adjusted so that the tension on spring 12 is sufficient to retain operating rod 9 in the position shown in Figure I.

Bracket 19 is rigidly attached to the truck body 40 and supports link 18 which is pivotably attached thereto at 20. Link 18 is also pivotably attached to operating rod 9 at 17 and to pull rod 22 at 21. Pull rod 22 extends to a point remote from discharge valves 1, usually to the opposite side or 45 end of the tank truck, and terminates in emergency handle 23.

The assembly operates as follows:

Referring particularly to Figures II and III, valve 1 is opened to permit flow therethrough by 50 swinging valve handle 5 outwardly, as shown in dotted outline in Figure II, then downwardly from the position shown in dotted outline in Figure III and finally inwardly and beneath projection 7 to the position shown in Figure II. The self-closing mechanism in valve 1 urges

handle 5 upwardly against projection 7, thus securing valve 1 in the open position, to close the valve, handle 5 is swung outwardly from beneath projection 7, whereupon the self-closing mechanism of the valve operates to raise handle 5 to the closed position, as shown in dotted outline in Figure III.

When one or more valves have been adjusted to the open position, the valve handles 5 thereof lie against contact plates 16 of arms 15 which are carried by operating rod 9. In the event of fire in the vicinity of the discharge valves, one or more of fusible metal links 14 will fail, thus releasing the tension on spring 12, which normally counters (tensions) the tension on spring 11. With the tension upon spring 12 released, spring 11 operates to move operating rod 9 to the right in Figure I, thus swinging handles 5 outwardly from beneath projections 7 by means of arms 15 and contact plates 16. As soon as handles 5 have cleared projections 7, the self-closing mechanisms of valves 1 operate to move handles 5 upwardly to the closed position. After having been activated, the safety mechanism may be reset by simply replacing the fusible link or links that have failed and retensioning spring 12. Although it is apparent that the safety mechanism will operate when springs 11 and 12 exactly countertension each other, in practice it has been found desirable to tension spring 12 to a degree appreciably in excess of spring 11 in order to prevent movement of operating rod 9 due to vibration of the truck in transit or similar mechanical vibrations.

In the event that fire near the discharge valves is noticed by the truck operator before the heat generated is sufficient to cause failure of one or more fusible links, all open valves may be simultaneously closed by means of emergency handle 23. Upon pulling emergency handle 23, rod 22 operates to pull one arm of pivotable link 18, the motion being transmitted through the other arm of pivotable link 18 and serving to pull operating rod 9 against the tension of spring 12, thus swinging handles 5 outwardly from beneath projections 7 and permitting the self-closing mechanisms of valves 1 to return valve handles 5 to the closed position.

I claim as my invention:

1. Activating mechanism for a plurality of control devices comprising a slideable rod, a plurality of arms on said rod, yieldable means urging said arms out of contact with said control devices and yieldable means urging said arms into contact with said control devices, and a heat responsive element in association with said first mentioned yieldable means whereby said first mentioned yieldable means is rendered inoperative upon a sufficient rise in temperature.

2. Activating mechanism for a plurality of control devices comprising a slideably mounted rod, arms rigidly attached to said rod, a spring urging said arms out of contact with said control devices, a spring urging said arms into contact with said control devices, and a thermally fusible metallic element countertensioning said first mentioned spring whereby said first mentioned spring may be rendered inoperative.

3. Activating mechanism for a plurality of control devices comprising a slideable mounted rod, a plurality of arms attached to said rod, a first spring attached to said rod urging said rod and arms in a direction such that contact with said control devices is avoided, a second weaker spring attached to said rod urging said rod and arms in the opposite direction whereby contact of said arms with said control devices will result, fusible metal elements in association with said first spring whereby said first spring will be rendered inoperative upon a sufficient rise in temperature in the vicinity of one or more of said fusible metal elements.

4. Activating mechanism for a plurality of control devices comprising a slideably mounted rod, a plurality of arms attached at right angles to the length of said rod, a first spring attached to said rod urging said rod and arms in a direction such that contact of each arm with each control device is avoided, a second weaker spring attached to said rod urging said rod and arms in the opposite direction whereby contact of each arm with each control device will result, a plurality of fusible metal links arranged in series with said first spring whereby said first spring will become released upon a sufficient rise in temperature in the vicinity of one or more of said fusible metal links.
